UNITED STATES PATENT OFFICE.

FERDINAND E. LAMMERT, OF CHICAGO, ILLINOIS.

INTERNAL-COMBUSTION ENGINE.

1,118,500.

Specification of Letters Patent. Patented Nov. 24, 1914.

Application filed January 13, 1914. Serial No. 811,813.

To all whom it may concern:

Be it known that I, FERDINAND E. LAMMERT, a citizen of the United States, residing at Chicago, in the county of Cook and State of Illinois, have invented a new and useful Improvement in Internal-Combustion Engines, of which the following is a specification.

My invention relates to an improvement in gas-engines used in conjunction with radiators, as they are on motor-cars or automobiles; and my object is to provide thermostatic means for so regulating the circulation, between the water-jacket of the engine and the radiator, of the hot water, that the predetermined temperature of the latter required for the engine shall remain without material variation under exposure to cold, moderate and hot weather.

In the accompanying drawings, Figure 1 is a view showing an automobile gas-engine and radiator in side elevation, and Fig. 2 is an enlarged view in elevation, partly sectional, of the thermostat-operated valve-device for controlling the hot-water circulation between the water-jackets and the radiator.

The engine-cylinders 3, 3 are shown in pairs, each pair being provided with a water-jacket 4. The radiator is shown at 5; and a rotary pump 6, having its shaft geared, as usual, to a motor (not shown), circulates the water through a pipe-connection 7 with the suction-side of the pump, and branch discharge-pipes 8, 8 through the water-jackets, which discharge through pipe-connections 9 and 9' into the radiator, thereby completing the circuit. At 10 is shown the usual rotary fan for forcing air through the radiator.

All the parts thus far described and their operation are too well known to require detailed description thereof in the present connection.

In the pipe 9, at the discharge-side from the engine, and in accessible position wherein it does not crowd other parts, is interposed a thermostat-controlled valve-device 11 of the preferred construction illustrated. Its casing 12, of semi-circular form, is provided with opposite nipples 13 and 14 for coupling it into the pipe 9. In the casing is secured at one end a semi-circular spring tube 15 closed at its ends and containing a fluid, such as ether or alcohol, which readily expands under the influence of heat and contracts under the influence of cold. The tube

used is the well-known Bourdon spring tube, which is employed in steam traps and steam and vacuum gages. On the opposite end of the tubular spring is a rectangular head 16 carrying loosely in its horizontal arm a headed stem 17 movable against a spiral spring 18 confined about it. With the head of this stem is pivotally connected the shorter arm of a bell-crank lever 19 fulcrumed at its angle in the casing and having a slotted member 20 adjustable thereon to extend and withdraw it and fastened in adjusted position by screws working through the slot. A link 21 connects the outer end of the member 20 with a butterfly-valve 22 of rectangular form preferably fulcrumed eccentrically, as shown, in the inner end of the nipple, which contains a stop 23 to properly limit the seating movement of the valve 22 on its pivotal support. This valve, which works between two flat surfaces of the opposite inner casing-walls, is slightly narrower than the inner diameter of the nipple 14 to leave a narrow space for leakage about the edge of the valve and prevent complete closure in its normal or "seated" position, for the purpose hereinafter explained.

Supposing the predetermined temperature for the water in the jackets 4 to be, say, about 180° F., the valve occupies the position illustrated when the temperature is somewhat below that specified. Then the pump maintains a constant circulation of the water through the radiator, but in such small quantity that by its return in cooled condition to the jackets, the temperature therein will nevertheless soon be raised to the predetermined degree. The normal condition of the thermostatic member 15 is such as to cause it, when cold, to maintain the valve against the stop 23, and tendency to any excessive pressure against the latter of the valve by contraction of that member is reduced by the spring 18. Whenever the temperature of the water in the jackets exceeds, more or less, the predetermined degree, expansion of the liquid in the spring-tube distends the latter accordingly and turns the bell-crank in the direction to open the valve and thereby increase the water-circulation through the radiator to cool a sufficient quantity thereof to reduce the temperature of the jacket-contained overheated water on returning thereto.

Among the more important advantages obtained by the use of my improvement in

connection with an automobile gas-engine, the following may be mentioned: In cold weather instead of having to wait, as heretofore, for the engine to warm up, or to ride 5 a considerable distance before the engine begins to run smoothly, it will either have the proper temperature or attain it very quickly. The engine uses less gasoline, because it always runs at the temperature conducive to 10 the greatest economy in the use of fuel. Loss of power due to an abnormally-cool engine is avoided, and the maximum power is available at all times without requiring to wait for the engine to heat up. The carbureter 15 may be adjusted "closer" (i. e. for the proper normal proportions of air and gasoline) and will not require readjusting, because the engine will run at the same temperature in winter and summer; and 20 since better operation of the carburetor ensues, there will be less carbonization, and therefore more power and less overheating. Moreover, by reason of there being less carbonization it is unnecessary to make the fuel-mixture so rich, to be slow-burning, as is 25 necessary where accumulated carbon becomes heated to a glowing temperature and prematurely ignites a mixture of the normal proportions of air and gasoline. 30 Finally, automobile builders will be saved the necessity of selecting a certain size of radiator to suit a certain engine, since they need only provide the radiator large enough for the hottest weather and depend on my 35 regulator for keeping the engine from running too cool for efficient operation at other times.

There is an object in pivoting the valve 22 off-center, as shown in Fig. 2. Thus, it 40 sometimes happens that an automobile-engine, when starting it in cold condition, will be momentarily speeded excessively. The resultant speed of the pump is then liable to be sufficiently high to create excessive pressure in the system requiring immediate relief to avoid its injuring the pump. Should such excessive pressure occur, the leakage which the valve affords will 45 not be sufficient to relieve it, but it will be

exerted upon and open the eccentrically pivoted valve against the resistance of the spring 18, thereby immediately relieving the pressure without affecting the thermostat; and the moment that this relief occurs, the recoil of the spring 18 will restore the valve. 55

I realize that considerable variation is possible in the details of construction thus specifically shown and described, and I do not intend by illustrating a single, specific or preferred embodiment of my invention 60 to be limited thereto; my intention being in the appended claims to claim protection upon all the novelty there may be in my invention as broadly as the state of the art will permit. 65

What I claim as new and desire to secure by Letters Patent is—

1. In combination with an internal-combustion engine and a radiator having a water-circulating connection with the engine-jacket, a casing, a valve in the discharge-end of the casing, a thermostat in the casing, and a spring-pressed lever and link connection of the thermostat with the valve to open and close the latter by variations in the temperature of the water in the jacket and operating to open the valve in opposition to the spring by excessive pressure against the valve. 75

2. In combination with an internal-combustion engine and a radiator having a water-circulating connection with the engine-jacket, a casing interposed in the discharge-side of said connection, a butterfly-valve pivotally supported to one side of its 80 median line in the discharge-end of the casing, a thermostat in the casing and a spring-pressed lever and link connection of the thermostat with the valve to open and close the latter by variations in the temperature 85 of the water in the jacket and operating to open the valve in opposition to the spring by excessive pressure against the valve. 90

FERDINAND E. LAMMERT.
